UNITED STATES PATENT OFFICE.

BENJAMIN LIPPER, OF PHILADELPHIA, PENNSYLVANIA, ASSIGNOR TO HIMSELF, AUGUSTUS A. LAZARUS, AND ISAAC A. SCHWARTZ, OF SAME PLACE.

DESIGN FOR DRESS-TRIMMING.

SPECIFICATION forming part of Design No. 22,071, dated December 20, 1892.

Application filed November 23, 1892. Serial No. 452,954. Term of patent 3½ years.

To all whom it may concern:

Be it known that I, BENJAMIN LIPPER, a citizen of the United States, and a resident of Philadelphia, Pennsylvania, have invented a new and original Design for Dress-Trimming, of which the following is a specification.

My design for a dress trimming is fully shown in the accompanying drawing, which represents a face view of a piece of the trimming. The trimming has opposite edgings composed of inner and outer rows of loops *a* and *b* and a central portion comprising a succession of oval or diamond-shaped figures *d* presenting a granulated surface, these figures alternating with loops forming representa-

tions of bow knots *f*, the figures *d* and bow knots *f* being the distinctive features of the design.

I claim:

The design for a dress trimming substantially as described and as shown in the accompanying drawing.

In testimony whereof I have signed my name to this specification in the presence of two subscribing witnesses.

BENJAMIN LIPPER.

Witnesses:

WILLIAM A. BARR,
FRANK E. BECHTOLD.
